US00D826244S

(12) **United States Design Patent** (10) Patent No.: **US D826,244 S**
 (45) Date of Patent: **** Aug. 21, 2018**

(54) **DISPLAY SCREEN OR PORTION THEREOF
WITH GRAPHICAL USER INTERFACE**

(71) Applicant: **YANDEX EUROPE AG**, Lucerne (CH)

(72) Inventor: **Alexandra Yurievna Yampolskaya**, Moscow (RU)

(73) Assignee: **Yandex Europe AG**, Lucerne (CH)

(**) Term: **15 Years**

(21) Appl. No.: **29/539,361**

(22) Filed: **Sep. 14, 2015**

Related U.S. Application Data

(63) Continuation of application No. 29/459,515, filed on Jul. 1, 2013, now Pat. No. Des. 740,841.
